UNITED STATES PATENT OFFICE.

EDWIN M. SHERMAN, OF CHICAGO, ILLINOIS, ASSIGNOR TO ACETYLENE APPARATUS MANUFACTURING COMPANY, OF CHICAGO, ILLINOIS, A CORPORATION OF WEST VIRGINIA.

CARBID-HOLDER.

No. 806,585.

Specification of Letters Patent.

Patented Dec. 5, 1905.

Application filed July 9, 1904. Serial No. 215,861.

To all whom it may concern:

Be it known that I, EDWIN M. SHERMAN, a citizen of the United States, residing at the city of Chicago, in the county of Cook and State of Illinois, have invented certain new and useful Improvements in Acetylene-Gas Generators, of which the following is a specification.

The principal object of the present invention is to provide a carbid-holder which is simple in construction, comparatively inexpensive, and efficient and which when used along with others in a series can be interchangeably employed with absolute certainty of proper relative arrangement.

To these and other ends hereinafter set forth the invention, stated in general terms, comprises the improvements to be presently described and finally claimed.

The nature, characteristic features, and scope of my invention will be more fully understood from the following description, taken in connection with the accompanying drawings, forming part hereof, in which—

Figure 1 is a perspective view of a carbid-holder embodying features of the invention. Fig. 2 is a top or plan view, drawn to an enlarged scale, of the same. Fig. 3 is a sectional view taken on the line 3 3 of Fig. 2. Fig. 4 is a sectional view illustrating several of the carbid-holders assembled one above the other, and Figs. 5 and 6 are respectively an elevation and a top view of the generator shown in Fig. 4.

In the drawings, 1 is an open-top receptacle shown as provided with a pivotal bail or handle 2 and having a centrally-disposed opening *a* at its base. This receptacle is divided by means of partitions into compartments, of which four—3, 4, 5, and 6—are shown, although the number is not material. One of these compartments—the compartment 3—includes said opening, so that the opening *a* is arranged centrally and the compartments are arranged eccentrically. Within the compartment 3 is arranged a housing 7, (shown as wedge-shaped,) which, however, is only a convenient form, and it constitutes a closed duct which communicates with the opening *a* and with the adjacent compartment 6 by way of the opening *a'*. The housing or duct 7 leaves the upper portion of the compartment 3 open at the center of the vessel or re-

ceptacle, so that water discharged into the vessel or receptacle centrally will fall into the compartment 3, thence by way of the openings *x* in the partition *b* into the compartment 4, thence by way of the openings *x* in the partition *c* into the compartment 5, thence by way of the openings *x* in the partition *c'* into the compartment 6, and thence by way of the opening *a'* in the partition *b'* into the duct 7. From the duct 7 the water passes by way of the centrally-disposed opening *a* in the base of the receptacle, and if there be another carbid-holder beneath the water will flow centrally into it and into its compartment 3 and will then traverse the path described with respect to the first receptacle, and there may obviously be any number of carbid holders or receptacles placed the one above the other. The partitions *b* *b'* and *c* *c'* may be made of strips of metal bent as shown, so as to leave straight walls *d*, which can be readily soldered together, and, furthermore, these partitions may be readily joined to the base and side wall of the receptacle, as by turning over a foot or flange on them which can be conveniently both soldered and riveted. The wall *d* and a portion of the partition *b'* can be employed as two sides of the closed housing or duct 7, and the latter can be readily soldered to place. Since the compartment 3 extends over or includes the central opening *a*, it follows that when a number of the described carbid-holders are placed the one above the other that they are necessarily in position for discharging water always into the compartments 3, no matter how they may be turned, and this is advantageous in assembling the holders. If desired, some of the compartments may be made wider than the others, so as to make their contents substantially equal, or, otherwise stated, the compartment 3, since it includes the center, is longer than the others; but, if desired, the others may be made wider, so as to compensate for this.

8 is a receptacle adapted to contain a series of the described carbid-holders placed the one above the other, and it is sealed, for example, by means of the cover 9, which is provided with a flange that depends into a water seal 10. This generating chamber or receptacle 8 is provided with an intake-pipe 11, which dips down beneath its seal and is arranged to discharge, as at 12, centrally of the

carbid-holder. The part 12 of this pipe may be arranged so as to turn in order to get it out of the way to permit of the lifting out and in of the carbid-holders. The gas generated in the chamber 8 may be led off, as by the pipe 13, and discharged through the perforated funnel 14 beneath the water at the base of the gas-holder tank 15 and under the housing 16, from which the gas rises by way of the pipe 17 and is discharged into the gas-holder 18. From the latter it is led by way of the pipe 19 through the gas-filter 20 for use.

21 is a safety-vent connection. The rise and fall of the holder 15 serves to turn the pipe 22 downward, so as to discharge water from the gas-holder tank into the pipe 11, and thus cause the generation of acetylene from carbid contained in the holders and upward, so as to interrupt such generation.

23 is the framework or gas-holder guide. The gas-holder tank is divided, as at 24, and the lower part contains water to about the level of the lip 25, so that any excess of gas-pressure would break through this water seal and escape, for example, by way of the pipe 26, which leads to the air.

It will be obvious to those skilled in the art to which my invention relates that modifications may be made in details without departing from the spirit thereof. Hence the invention is not limited other than the prior state of the art may require; but,

Having thus described the nature and objects of my invention, what I claim as new, and desire to secure by Letters Patent, is—

1. A carbid-holder for acetylene-gas generators comprising a receptacle having compartments of which one extends from its rim and includes the center of the base of the receptacle and a closed duct arranged in the last-mentioned compartment and adapted to externally shed fluid to said compartment and to internally convey fluid from an adjacent compartment and discharge it centrally of the base, substantially as described.

2. A carbid-holder for acetylene-generators comprising a receptacle having a centrally-disposed opening in its base and having partitions extending from its rim dividing it into compartments of which one includes said opening, and a closed duct arranged in the last-mentioned compartments and having communication with said opening and by way of a port in one of said partitions with an adjacent compartment, substantially as described.

3. A carbid-holder for acetylene-generators comprising a receptacle having a centrally-perforated base and having a closed housing over said perforation and having unsymmetrically or eccentrically arranged compartments of which one contains said housing, substantially as described.

4. A carbid-holder for acetylene-generators comprising a receptacle having com-

partments of which one extends from its rim and is open at its top and closed at its bottom over the center of the base and of the receptacle, and a duct leading from an adjacent compartment and discharging at the center of the base of the receptacle, substantially as described.

5. A carbid-holder for acetylene-generators comprising a receptacle having a centrally-disposed opening in its base and having unsymmetrically or eccentrically arranged partitions, and a closed duct communicating with said opening and merging into and communicating through one of the partitions, substantially as described.

6. A carbid-holder for acetylene-generators comprising a receptacle having an opening at the center of its base, perforated partitions subdividing the receptacle into compartments of which one extends from the rim and includes said opening, and a housing arranged over said opening and having communication through one of said partitions, substantially as described.

7. A carbid-holder for acetylene-generators comprising an open-top receptacle having an opening centrally disposed in its base, partitions consisting of bent strips each having abutting walls which are connected together, said partitions constituting compartments of which one includes the opening and extends to the rim, and a housing communicating with said central opening and by way of a port through one of said partitions, substantially as described.

8. In an acetylene-generator, a generating-chamber provided at its top with a centrally-arranged water-discharge pipe, and a series of carbid-holders arranged one above the other in said chamber and each provided at its base with a central perforation and each subdivided into compartments of which one extends from the rim and includes said opening and each provided with a housing communicating with said opening and with an adjacent compartment, each compartment that contains the housing receiving water from above, substantially as described.

9. A carbid-holder comprising a receptacle having a central opening in its base and having compartments extending to its rim and of which one includes said opening and of which the others are wider than the first-mentioned compartment to make their contents substantially equal, and a closed housing communicating with said opening and through the partition-wall of one of said compartments, substantially as described.

In testimony whereof I have hereunto signed my name in the presence of two witnesses.

EDWIN M. SHERMAN.
